UNITED STATES PATENT OFFICE.

ARCHIBALD F. MESTON, OF NEW YORK, N. Y., ASSIGNOR TO RESEARCH CORPORATION,
OF NEW YORK, N. Y., A CORPORATION OF NEW YORK.

MEANS FOR REMOVING DEPOSITS FROM ELECTRODES.

1,339,471.

Specification of Letters Patent. Patented May 11, 1920.

Application filed October 23, 1917. Serial No. 198,157.

To all whom it may concern:

Be it known that I, ARCHIBALD F. MESTON, a citizen of the United States, residing at New York, in the county of New York and State of New York, have invented certain new and useful Improvements in Means for Removing Deposits from Electrodes, of which the following is a specification.

10 The present invention relates to apparatus for separating dust, soot or other solid or liquid particles from gases by electrical action. It is a common experience that in apparatus of this kind, although most of the particles drop to the bottom 15 of the precipitator and are then removed from the apparatus or settle on the collecting electrodes and are then jarred therefrom by hammers or knockers, some of the particles adhere to the discharge electrode or electrodes and gradually form a deposit 20 in spite of the action of the electric charge tending to force them away. Such deposit is detrimental to the operation of the apparatus.

It is the object of the present invention to provide means for jarring off dust, soot or other particles from discharge electrodes of an electric precipitator. It is the particular 30 object to provide a system of hammers or knockers which does not interfere with the operation of the precipitator, does not affect the insulation of the discharge electrodes from the collecting electrodes or the ground 35 and is simple in construction and operation.

I carry out the above objects by housing the knocker-system in the precipitating chamber closely associated with the discharge electrodes and insulating it in common 40 with the discharge electrodes from the remaining structure.

For a fuller understanding of the invention reference is had to the accompanying drawings in which

45 Figure 1 is a vertical section through a precipitator embodying the invention;

Fig. 2 a horizontal section through the device shown in Fig. 1;

50 Fig. 3 a diagrammatic representation of electrical connections for operating the knocker system, and

Figs. 4 and 5 show a modified form of electrode system to which the invention is applied.

55 In Figs. 1 and 2, which represent merely in conventional form a precipitator, 1 is the

treater chamber, 2 the collecting electrodes and 3 the discharge electrodes. These discharge electrodes may be suitably supported from a frame 4 of conducting material, as 60 is usual, which frame is insulated from the chamber by insulators 5. The discharge electrodes extend centrally through the collecting electrodes 2 represented as tubes or pipes and are connected to a common frame 65 or platform 6 which is of insulating material, although this is not essential. This platform, which holds the discharge electrodes taut, is connected by strain insulators 7 to the walls of the chamber and held there- 70 by in fixed position.

The knocker system comprises a plurality of knockers or hammers 8, one for each discharge electrode. Each hammer has two heads 9 and 10 adapted to strike the electrodes from opposite sides. While these hammers may be supported in various ways, I prefer to mount them in pairs on bars 10' 75 carried by cross bars 11. This supporting frame is mounted for oscillating motion on 80 uprights 12 through levers 13 and 13' pivoted thereto. On the platform 6 is mounted a solenoid device inclosed in a casing 14. This solenoid device is composed of two coils 15 and 16 and a common core 17 shown detached in Fig. 3 for the purpose 85 of clearness. The core is attached by links 18 and 19 to rods 20 and 21 respectively, which rods are in turn pivotally connected 90 to levers 13 and 13' at the lower end thereof.

As shown on an enlarged scale in Fig. 3, the core 17 has a projection 22 extending outwardly between the coils. Opposite the projection is pivotally mounted a U-shaped contact switch 23. The coils 15 and 16 have terminals 24 and 25 spaced from each other a distance slightly greater than the distance between the legs of the switch so that the legs may alternately contact with one of the terminals. The switch is pivoted on a 100 conductor bar 26 and a spring 27 may be interposed between the bar and the switch to insure a good contact between one coil terminal and the switch terminal 24'. Current connections are made to the bar 26 105 and the outer ends of the coils 15 and 16, as indicated schematically in Fig. 3. The solenoids are so designed that, when current passes through the coil 15, the core is forced toward coil 16. The projection on 110 the core thereby strikes leg 24' of the switch and forces it against contact 25. The cur-

rent will now pass through coil 16 and the core will be forced toward coil 15. This operation will continue, like in the ordinary make and break device, so long as current is supplied. The motion of the core is transmitted, as before stated, to the swinging knocker frame and the knockers or hammers are caused to strike the electrodes alternately from one side and then from the other. The impact of the hammers on the electrodes causes vibration of the electrode and jars the deposit from them.

The particular nature of the electromagnetic means for operating the knocker system is not material, since vibrating or oscillating mechanisms of this kind are well known in the art.

To operate the electro-magnetic device without impairing the insulation of the high tension electrode system I use the discharge electrodes themselves. 30 is a generator, 31 the primary winding and 32 the secondary or high voltage winding of a transformer. A double throw-switch comprising the common terminals *a*, *b*, the terminals *c*, *d* of the low voltage circuit and the terminals *e*, *f* on the high voltage circuit. From the terminal *a* a connection is made through the conducting frame 4 to the electrode 3' and from the terminal *b* to the electrode 3''. The electrode 3' is connected to the conductor bar 26 and the electrode 3'' makes connection to the outer ends of the coils 15 and 16 through a wire 26'. The electrode 3'' is insulated from the conductor bar 4 in any suitable manner, an insulating bushing 33 being shown in Fig. 1 merely as a suggestion.

When the switch A is thrown into contact with the terminals *c*, *d*, current will pass from the low voltage source through electrode 3' to the bar 26, then through contact 24 into coil 15 and from coil 15 through wire 26' to electrode 3'' and back to the source, or vice versa.

When the switch A is thrown to the left into contact with the high voltage terminals *e*, *f*, which are short circuited by wire *g*, one pole of the high voltage winding 32 is connected through wire *h* with both electrodes 3' and 3'', the other pole of the transformer winding 32 being connected to ground G, as usual, to complete the circuit through ground G' and the collecting electrodes 2 via the chamber structure 1. Since all the electrodes, except 3'' are positively interconnected through the bars 4 of the supporting structure, and electrode 3'' is charged through the wire *g*, the discharge electrode system is uniformly charged. Electrical connection is, of course, also made between electrodes 3' and 3'' through the solenoid device, but I prefer to short circuit them through wire *g* in addition to that.

It is thus seen that the knocker system is

introduced into the high voltage system without in the least impairing the insulation of it. The conductors *m* and *n* may be carried in a single cable (not shown) as they must be insulated from each other only for the voltage of the primary source.

Figs. 4 and 5 show the invention embodied in a slightly different way. The discharge electrodes are in the form of wires 40 surrounded by pipes 40' to make them rigid and durable. The corner electrodes 40' are made of larger diameter and greater rigidity for the purpose of supporting the knocker system, which is in all respects similar to that shown in Figs. 1 and 2. The cross bars 42 are pivotally supported on arms 43 which are pivoted to the electrodes 40''. Bars 44 interconnect the cross bars 42 and carry the knockers 45. Since the corner electrodes are of larger diameter than the other electrodes, the heads of the knockers co-operating with them are spaced farther apart than the heads of the other knockers so that all heads may simultaneously strike their electrodes. The corner electrodes are shown out of alinement with the other electrodes, although this feature is not material. The knockers 45' are therefore bent to bring the heads into proper position.

The electromagnetic device and the connections for operating it are identical with the arrangement shown in Figs. 1 and 2 and therefore omitted.

The foregoing is intended merely as an illustration of the principle on which the invention is based and of one way in which it may be carried out. The details of the knocker system may be varied within wide limits, the operating mechanism may be replaced by different types of electro-magnetic devices and the connections altered correspondingly. The invention is applicable to all forms of electrodes.

In order to operate the jarring device to clean the discharge electrodes it is only necessary to throw over the switch A from the high to the low voltage side of the transformer and after a few seconds throw it back. This may be done as often as desired without materially interrupting the operation of the precipitator.

While I have shown the knocker or hammer system mounted at the lower end of the electrodes, it is obvious that it may be supported by the electrode system at the upper end thereof as for instance from the frame 4 by suitably increasing the distance between the frame 4 and the upper end of the collecting electrodes 2. The invention may be applied to a single discharge electrode by merely making the electrode of two conductors insulated from each other for the voltage of the primary circuit. A convenient arrangement for this purpose would be that

shown in Figs. 4 and 5. Wire 40 could be insulated from pipe 40' so as to lead the current to and from the solenoid device like electrodes 3' and 3" respectively. These 5 features do not involve any material modification of structure or operation, but are only referred to to show an obvious adaptation.

In the preceding description the current 10 used for operating the hammer system has been derived from the low voltage side of a transformer, the high voltage side of which is normally connected to the discharge electrode system, the usual rectifier being omitted for the sake of simplicity. It is understood that in place of an alternating current system a high tension D. C. system may be used in which case the current for operating the hammer system may be derived 15 from any suitable low tension source.

I claim:—

1. In an electric precipitator comprising a collecting electrode and a discharge electrode, means for striking the discharge electrode intermediate its ends to cause vibration thereof.

2. In an electric precipitator comprising collecting electrodes and discharge electrodes, means for striking the discharge electrodes intermediate their ends to cause vibration thereof.

3. In an electric precipitator comprising a collecting electrode, a discharge electrode, an electric connection to said discharge electrode, means constructed and arranged to jar the discharge electrode and means for operating said jarring means through the agency of said electric connection.

4. In an electric precipitator comprising 40 a collecting electrode, a discharge electrode, a device for jarring the discharge electrode electrically connected with the discharge electrode and electrically separated from the collecting electrode and electrical means for 45 operating the jarring device.

5. In an electric precipitator comprising collecting electrodes and discharge electrodes, means constructed and arranged to jar the discharge electrodes and means for 50 operating said jarring means through the agency of the discharge electrodes.

6. In an electric precipitator comprising collecting electrodes and discharge electrodes, hammers supported in position to 55 strike the discharge electrodes and means for operating the hammers through the agency of the discharge electrodes.

7. In an electric precipitator comprising collecting electrodes and discharge electrodes, hammers for striking the discharge 60

electrodes, a support for the hammers carried by the discharge electrodes and means for operating the hammers through the agency of the discharge electrodes.

8. In an electric precipitator comprising 65 collecting electrodes and discharge electrodes, a frame connected with the discharge electrodes, a system of hammers movably mounted on the said frame and adapted to strike the discharge electrodes, and means 70 for moving the said system through the agency of the discharge electrodes.

9. In an electric precipitator comprising collecting electrodes and discharge electrodes, a frame connected with the discharge 75 electrodes, a system of hammers supported by said frame for swinging motion transversely of the electrodes and adapted to strike the discharge electrodes and means for moving the said system through the 80 agency of the discharge electrodes.

10. In an electric precipitator comprising collecting electrodes and discharge electrodes, a frame connected with the discharge electrodes, a system of hammers movably 85 mounted on the said frame and adapted to strike the discharge electrodes, electro-magnetic means mounted on said frame for moving the said system and means for operating the said electro-magnetic means through 90 the agency of the electrodes.

11. In an electric precipitator comprising collecting electrodes and discharge electrodes, a frame connected with the discharge electrodes, a system of hammers movably 95 mounted on the said frame and adapted to strike the discharge electrodes, electro-magnetic means supported by said frame for moving the said system and means whereby, at the will of the operator, the discharge 100 electrodes may be charged or the electro-magnetic means may be operated to move the said system.

12. In an electric precipitator comprising collecting electrodes and discharge electrodes, a frame connected with the discharge electrodes, a system of hammers movably mounted on the said frame and adapted to strike the discharge electrodes, electro-magnetic means supported by said frame for 105 moving the said system, means for connecting two of the electrodes to the electromagnetic means, means for selectively insulating the said two discharge electrodes relatively to each other and means for connecting the 110 said two electrodes to a current supply when they are relatively insulated.

In testimony whereof I affix my signature.

ARCHIBALD F. MESTON.
